(57) **CLAIM**

The ornamental design for a cap, as shown and described.

DESCRIPTION

FIG. 1 is a top front and side perspective view of a cap;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is bottom plan view thereof.

The broken lines are shown for the purpose of illustrating parts of the cap that form no part of the claimed design.

1 Claim, 7 Drawing Sheets
